BRACELET

Hyman R. Wishengrad, Mount Vernon, N. Y.

Application March 27, 1951, Serial No. 14,637

Term of patent 3½ years

(Cl. D45—4)

To all whom it may concern:

Be it known that I, Hyman R. Wishengrad, a citizen of the United States, residing in Mount Vernon, county of Westchester, State of New York, have invented a new, original, and ornamental Design for a Bracelet, of which the following is a specification, reference being had to the accompanying drawing, forming a part hereof.

Fig. 1 is an exploded top plan view of a bracelet embodying my new design;

Fig. 2 is an exploded side elevational view thereof illustrating the central container in a partially open position; and

Fig. 3 is a side elevational view illustrating the bracelet in wearing position.

I claim:

The ornamental design for a bracelet, as shown and described.

HYMAN R. WISHENGRAD.
